UNITED STATES PATENT OFFICE.

ARTHUR E. SMITH, OF PITTSBURG, KANSAS, ASSIGNOR TO CLAUDE A. SMITH, OF PITTSBURG, KANSAS.

METHOD OF AND MEANS FOR PREPARING MEDICINAL AND ANÆSTHETIC SOLUTIONS.

Application filed December 16, 1922. Serial No. 607,391.

To all whom it may concern:

Be it known that I, ARTHUR E. SMITH, a citizen of the United States, residing at Pittsburg, in the county of Crawford and 5 State of Kansas, have invented certain new and useful Improvements in Methods of and Means for Preparing Medicinal and Anæsthetic Solutions, of which the following is a specification.

10 This invention relates to a method of and means for preparing medicinal and anæsthetic packages. The invention is of particular value in the preparation of anæsthetic solutions used in dental nerve blocking work but its usefulness extends beyond that particular field, as will be presently apparent.

United States Patent No. 1,243,349, is-
sued to me on the 16th day of October, 1917, 20 described a nerve blocking tablet, having combined therein the necessary chlorides to make Ringer's solution, a vaso constricting agent, such as suprarenin or adrenalin, for example, and an anæsthetic, such as novocain for example, all in such proportions that when a tablet is dissolved in a definite and predetermined amount of distilled water a solution isotonic to the blood is produced. However, it has been found that it has not 30 been a simple matter for the dentist to produce as required, absolutely pure distilled water in accurate quantity and to keep it free of contamination until used. Particularly is this true if the condition of the patient 35 is such as to require the dentist to treat the patient in the home, where no office or laboratory appliances are available.

It is, therefore, a primary object of the present invention to combine, as a unit, the necessary amount of pure distilled water and the necessary ingredients to be mixed therewith and to maintain them separate until the time of use arrives, the container and the separating means being of such a 45 nature that mixing of the water and the other ingredients may be effected with ease and dispatch and without subjecting the resultant solution to the air, until the moment of use arrives.

50 In order that the advantages of the forward step made in the art by this invention, may be better appreciated, it is pointed out that to secure safe and certain results in nerve blocking anæsthesia the following 55 must be observed:

First: For safety and the best results the solution must be fresh at the time of use. In other words the water and the other ingredients must not be brought together until the time of use arrives, or substantially so. The importance of having the solution fresh at the time of use is well recognized in the dental and medical professions and in the literature relating thereto. On page 463 of Prinz's textbook entitled 60 "Dental Materia Medica and Therapeutics," third edition, the following is found:

"The practitioner is especially cautioned in regard to the use of local anæsthetics in the form of ready made solutions. Solutions of cocaine, even when rendered sterile by fractional sterilization, will not remain so after the contents of the bottle are exposed to the air for a short time. Ready made solutions that are sold in the shops 70 under more or less fanciful names require still greater precautions. The recently enacted pure food and drug act requires that all solutions containing cocaine, eucain, and other similar alkaloids, must be labeled. 75 Most of the many, so called, safe and reliable anæsthetics found in the market, contain cocaine or its substitute in various quantities. The addition of adrenalin to a ready made solution not only destroys this alkaloid in a very short time, but the product of its decomposition with the decomposed cocaine makes the solution still more dangerous. The printed formulas that accompany 80 many of the ready made solutions of local anæsthetics frequently show an utter disregard of the pharmacologic action of the individual ingredients which forces us to conclude that they are a slur on the intelligence of the practitioner who uses such compounds." 85

Quoting Fischer from his textbook entitled "Local Anæsthesia in Dentistry," page 48 in 1914 edition,

"Synthetic suprarenin is stable only to a limited degree after the bottle has once been opened; for this reason the transferring into another vessel of the quantity required in every case, as recommended by Seidel, seems impracticable. In private practice it is best to make a fresh solution from tablets, as cases present themselves. 'The very convenient tablets,' as Braun writes, 'are preferable to any other form of dispensing alkaloids used for medical purposes. This is espe- 100 105 110 115

cially true of unstable drugs like suprarenin which, in dry tablet form, keep for a long time."

Same author from page 53:

5 "Numerous solutions in the market not only contain admixtures of highly toxic drugs, but also lack sufficient neutrality; in other words, they are not isotonic but heterotonic. Novocain-suprarenin solutions which 10 are intended for injection must always be of the purest quality; they must be crystal clear and not contain any admixtures nor must they have come in contact with any impurities during the process of preparation."

15 Same author from page 55:

"For the requirements of daily practice it seemed expedient to dispense novocain-suprarenin in ampules so as to offer the solution ready for use in convenient form. 20 Our experiences with these ampules, however, induce us to give the preference to solutions freshly made from tablets, for the present at least. The ampule solution decomposes more quickly and its stability depends upon the conditions of temperature 25 and light under which it is preserved. Suprarenal extract is not stable for any length of time when in liquid union with novocain."

30 Same author page 41:

"The preparations marketed in ampules are somewhat untrustworthy, according to recent opinions, because their stability is a limited one. For this reason freshly made 35 solutions are absolutely preferable to all stock solutions."

Second: The resultant solution must be isotonic to the blood; i. e., the amount of water used must be in such proportion to 40 the chlorides which form the Ringer's solution that the solution will not be hypertonic, or concentrated, so as to contain more of the chlorides than are found in an equal amount of blood. It is necessary in the use 45 of a local anaesthetic solution of this nature to have it conform to the chlorides (salts) in the blood. If the solution is not isotonic, then the osmotic pressure of the solution will be different from that of the surrounding 50 tissues and will cause pathological changes in the blood and other tissues, that are highly undesirable. A local anaesthetic solution when injected should not produce 55 pathologic tissue changes and should conform to the physical and physiological laws of the living cells comprising the various tissues.

Third: The water used must be absolutely pure, distilled water, to begin with 60 and must be maintained in a sterile and uncontaminated condition.

Broadly speaking the invention consists 65 of enclosing within any suitable container any two or more substances one of which at least is liquid and separating one or more

of the substances from the other or others, until the time of use arrives, by a fusible wall of a material which will retain its form and solidity under ordinary temperatures but may be melted at higher temperatures. 70 When the time of use arrives this separating wall is melted by the application of heat and the contents of the package or container are mixed, and the package is opened, and its contents used.

I preferably embody the foregoing invention in the form of an ampule of glass and in the particular embodiment of the invention illustrated in the accompanying drawing some of the ingredients, whether in the 80 form of a powder, liquid, tablet or otherwise, are enclosed within a capsule of chemically pure paraffin by which the contents of the capsule are maintained in their original state until the time of use arrives. The 85 enclosing of the constituent elements of the package in an ampule not only protects its contents from contact with the outside air but, since these ampules are commonly sealed under a vacuum, it insures that no 90 air will be in contact with the substances within the ampule during the time that the article is in stock.

In the accompanying drawing:

Fig. 1 is a view partly in side elevation and partly in section of an ampule embodying one form of the invention and illustrating the same before the ampule is subjected to heat;

Fig. 2 illustrates the ampule after having been subjected to heat and cooled as herein-after described; and

Fig. 3 is a view of the empty package after the contents have been removed for use.

In carrying out the invention, in the particular form illustrated in the drawing, I provide an ampule 5, of glass, which may be of any desired color and free of alkali. This 110 ampule is provided with a neck extension 6 which may be readily broken therefrom after being slightly nicked with a small file. A capsule 7, of chemically pure paraffin, receives one or more tablets, indicated at 8, and the body of the ampule receives distilled water 9, which is sterile and free of all foreign substances. After the water and capsule have been placed in the ampule, the ampule is sealed, under a vacuum, at its neck portion 6, by fusing the glass together in a manner well known in the art. While I have stated that the capsule 7 contains a tablet or tablets it is manifest that it may receive the necessary material in powder or liquid form. Where the ampule is to be used 115 in nerve blocking work the material contained within the capsule 7 will contain, as before stated, the necessary chlorides to produce a Ringer's solution, a vaso constricting ingredient and an anaesthetic, and these will 120 125 130

be in such proportions to the amount of distilled water contained within the ampule that the resultant solution will be isotonic to the blood. However, if an anæsthetic 5 solution of a different type from that employed in nerve blocking work is desired, the invention is still of utility, since any suitable material may be placed within the capsule 7 and mixed with the water only 10 when the time of use arrives, as will be presently set forth. In other words, the invention, while being of particular utility in connection with dental nerve blocking work, is not necessarily limited thereto, but 15 has a wide range of usefulness, since it provides means to enable any physician or dentist to easily and quickly prepare solutions of many kinds which will have the advantage of being freshly prepared from fresh, 20 uncontaminated ingredients, irrespective of what the particular material contained within the capsule 7 may be.

When the time of use arrives, the ampule shown in the drawing is placed in water in 25 a sterilizer and boiled or held in running hot water, with the result that the paraffin capsule is melted and the water comes into contact with the tablets or other contents of the capsule. Thus a fresh Ringer's solution is 30 prepared at the same time that the local anæsthetic and the vaso-constricting ingredients are dissolving. The resultant solution is isotonic to the blood because, since the ampule is sealed, none of the distilled 35 water can be lost by evaporation or spilling. Since the contents are tightly sealed in the ampule, the ampule may be taken to the home of the patient and there boiled, with safety, in any domestic vessel.

40 After the ampule has been boiled for a sufficient length of time it is placed upside down or in the position illustrated in Fig. 2, in a glass of cold water, or is held in cold running water, or otherwise chilled, where- 45 upon the paraffin solidifies and forms a lump at the upper end of the ampule, being completely separated from the solution. The paraffin being of a lesser specific gravity than water will float on the surface of the 50 water and will solidify when the tempera- ture is lowered. Then the ampule is turned right side up, its neck portion 6 is nicked with a small file and the neck portion is broken off. The contents may then be 55 drawn into the hypodermic syringe, without ever having had the solution leave its original container. It is well known that the pouring of solutions of this character from one container into another offers a chance 60 of contamination. The boiling of the am- pule in the sterilizer can take place at the same time that the instruments to be used in the operation are being sterilized. Thus time is saved. When the ampule is placed in 65 cold water after it is removed from the

sterilizer the solution is quickly cooled. Consequently little time, or even no time, is lost. The same action which congeals or solidifies the paraffin, cools the hot solution to the temperature of the body, so that it 70 can be injected. Under the old method, where the solution was prepared in a porcelain cup or crucible, considerable time was lost while waiting for the solution to cool. 75

While, as before stated, the method and means herein described are of utility in preparing medicinal solutions in general, I desire to make it clear that the contents of the capsule, when the resultant solution is to be 80 used in dental nerve blocking work, consists of an anæsthetic of a suitable character, such as novocain or anocain, a vaso- 85 constricting ingredient, which may be supra- renin or adrenalin hydro-chloride and a 90 chloride or chlorides, in such proportion as to render the resulting solution isotonic to the blood. All of the chlorides of Ringer's 95 solution may be used or any of the chlorides which are used in making a Ringer solution. For example, sodium chloride alone may be employed, but the best results are secured by employing all the Ringer chlorides. 100

While I have described a capsule of 105 paraffin as the separating fusible medium, the non-liquid constituent may be in the form of a single tablet of the proper size and this may be dipped and redipped in melted paraffin until it is covered and en- 110 cased within a waterproof wall of paraffin. Furthermore, other material than paraffin may be used. It is only necessary that the material be of a nature to retain its form under ordinary temperatures, be fusible un- 115 der the application of heat and be non- miscible with the contents of the ampule.

I desire to lay particular stress upon the 120 fact that the invention is not limited to use in the preparation of medicinal packages containing anæsthetics, but that it has a wide range of usefulness in packaging any medicinal preparation which it is desired to mix fresh at the time of use. For example, digitalis is susceptible to deterioration and it is highly desirable in the use of this drug 125 that it be freshly mixed with pure distilled water at the time of use. Thus an ampule containing a body of distilled water and a capsule containing digitalis would come within the scope of the invention and be of great utility. There are many other drugs which in concentrated form retain their strength and other properties indefinitely but which deteriorate when mixed with distilled water or other ingredients. Furthermore it is within the scope of the invention to use other liquids than distilled water as the main body of liquid. For example, the chlorides of Ringer's solution might be 130 mixed with the distilled water and this con-

stitute the main body of liquid and the capsule contain tablets comprising only the anaesthetic and suprarenin; or the suprarenin (vaso-constricting agent) might be contained alone in the capsule, while having the water contain the anaesthetic and the Ringer's constituents. Any of these modifications are contemplated by me and are within the scope of the invention.

10. It is to be understood that the invention is not limited to the use of any specific form of container or shape of ampule, since these may be varied within wide ranges and still come within the scope of the invention defined by the following claims.

Having described by invention what I claim is:

1. The herein described method of putting up the ingredients of an anaesthetic solution which consists of placing in a container liquid and non-liquid constituents, and separating them by a wall, fusible at a point materially below the fusion point of the material of the container.

2. The herein described method of putting up the ingredients of an anaesthetic solution which consists of placing in a container liquid and non-liquid constituents and enveloping the non-liquid constituent by a water-proof wall, fusible at a point materially below the fusion point of the material of the container.

3. The herein described method of putting up the ingredients of an anaesthetic solution which consists of placing in a water-proof container distilled water and a non-liquid constituent in predetermined proportions and enveloping the non-liquid constituent with a water-proof wall of material fusible at a point materially below the fusion point of the material of the container.

4. The herein described method of putting up the ingredients of an anaesthetic solution which consists of placing in a water-tight container distilled water and a non-liquid constituent in predetermined proportions and enveloping the non-liquid constituent with a wall of chemically pure paraffin.

5. The herein described method of putting up the ingredients of an anaesthetic solution which consists of placing distilled water and a non-liquid ingredient in a hermetically sealed container, the non-liquid ingredient being enclosed in a capsule of pure paraffin.

6. In combination a sealed container of glass containing a liquid ingredient and a non-liquid ingredient, the non-liquid ingredient being separated from the liquid ingredient by a water-proof wall fusible at a point materially below the fusion point of the material of the container.

7. In combination a sealed glass container consisting of a liquid ingredient and a non-liquid ingredient, the non-liquid ingredient

being separated from the liquid ingredient by a wall of chemically pure paraffin fusible when the container is subjected to a temperature materially above normal.

8. In combination a sealed glass container containing distilled water and solid ingredients comprising one or more of the chlorides of Ringer's solution, a vaso-constricting ingredient and an anaesthetic, the solid contents of the container being separated from the distilled water by a wall of material fusible when the container is subjected to boiling and which will solidify and separate from the distilled water at ordinary temperature.

9. In combination a sealed glass ampule containing distilled water and a capsule of a material fusible at a point materially below the fusion point of the material of the ampule, said capsule containing and preserving in a dry state until used, the chlorides of Ringer's solution, a vaso-constricting ingredient and an anaesthetic all in such proportions that when the contents of the capsule are dissolved in the distilled water a solution isotonic to the blood is produced.

10. In combination a sealed glass ampule containing distilled water and a capsule of a material fusible at a point materially below the fusion point of the material of the ampule, said capsule containing and preserving in a dry state until used, the chlorides of Ringer's solution, a vaso-constricting ingredient and an anaesthetic all in such proportions that when the contents of the capsule are dissolved in the distilled water a solution isotonic to the blood is produced, said ampule having a breakable neck extension.

11. A hermetically sealed ampule containing distilled water and a capsule of material fusible when the ampule is heated but which solidifies and forms a homogeneous lump in the water when the temperature of the water is reduced, said capsule containing an anaesthetic ingredient which is in predetermined proportions to the amount of water.

12. A hermetically sealed ampule containing distilled water and a capsule of material fusible when the ampule is heated but which solidifies and forms a homogeneous lump in the water when the temperature of the water is reduced, said capsule containing an anaesthetic ingredient which is in predetermined proportions to the amount of water and said ampule having a breakable and reduced neck extension.

13. The herein described medicinal package comprising a sealed container containing two separate ingredients one at least of which is liquid and one of which is separated from the other by a wall fusible at a point materially below the fusion point of the material of the container.

14. The herein described medicinal package comprising a sealed container containing two separate ingredients one at least of which is a liquid and one of which is separated from the other by being incased within a casing fusible at a point materially below the fusion point of the material of the container.

15. The herein described medicinal package comprising a sealed container containing two or more ingredients one at least of which is liquid and one of which is enclosed within a casing fusible at elevated temperature but at a point materially below the fusion point of the material of the container and non-miscible with the liquid.

16. The herein described medicinal package comprising a sealed container, sealed in vacuo, containing two separate ingredients, one at least of which is liquid and one of which is separated from the other by being enclosed within a casing, fusible at elevated temperature and non-miscible with the liquid, said casing being fusible at a point

materially below the fusion point of the material of the container.

17. A medicinal package comprising a container and two ingredients, therein, which are to be kept separate until the time of use, and a wall of fusible material disposed between said ingredients and separating them, said material being fusible at a point materially below the fusion point of the material of the container.

18. The herein described method of producing fresh sterile solutions which consists of placing some of the ingredients of the solution in a container and there separating them by a wall of material fusible at a temperature above normal but at a temperature materially below the fusion point of the container so that by subjecting the container to an elevated temperature, the wall may be fused and the ingredients permitted to mix.

45 In testimony whereof I affix my signature.

ARTHUR E. SMITH.
